DISPLAY PACKAGING CONTAINER

John Donald Bostrom, Niles, Ill., assignor to Poster Packaging, Inc., Chicago, Ill., a corporation of Delaware

Filed Feb. 1, 1961, Ser. No. 63,789

Term of patent 14 years

(Cl. D58—11)

FIG. 1

FIG. 2

FIG. 3

FIG. 4

FIG. 1 is a perspective view of a display packaging container embodying my new design;

FIG. 2 is a top plan view thereof;

FIG. 3 is a bottom plan view thereof; and

FIG. 4 is an enlarged cross sectional view taken along the line 4—4 of FIG. 2.

The bottom for the container, not shown, is plain.

The essential features of my design are shown in full lines in the drawings.

I claim:

The ornamental design for a display packaging container, as shown and described.
